UNITED STATES PATENT OFFICE.

WILLIAM E. SMITH, OF MILLTOWN, NEW JERSEY, ASSIGNOR TO KILBOURN MANUFACTURING CORPORATION, OF NEW BRUNSWICK, NEW JERSEY, A CORPORATION OF NEW JERSEY.

CIRCULAR-KNITTING MACHINE.

1,121,681.

Specification of Letters Patent.

Patented Dec. 22, 1914.

Application filed December 4, 1913. Serial No. 804,723.

To all whom it may concern:

Be it known that I, WILLIAM E. SMITH, a citizen of the United States, residing at Milltown, in the county of Middlesex and State of New Jersey, have invented new and useful Improvements in Circular-Knitting Machines; and I do hereby declare the following to be a full, clear, and exact description of the invention, such as will enable others skilled in the art to which it appertains to make and use the same.

My invention consists in the novel features hereinafter described, reference being had to the accompanying drawings which show several embodiments of the invention, which I have selected for the purpose of illustrating the same, and the said invention is fully disclosed in the following description and claims.

20 The primary object of my invention is to provide means whereby the gage of the stitches drawn by the needles of a circular knitting machine may be increased to a greater or less extent in a portion of any 25 course or courses without increasing the gage of the stitch drawn by other needles in the same course or courses.

The application of my invention is very far reaching in that it may be used for increasing 30 the gage of the stitch drawn by a portion of the needles of a circular series, for the purpose of facilitating the introduction of a reinforcing thread, or for accommodating a thicker yarn in a portion of the stocking, both without increasing the length of 35 the fabric containing the reinforcing or thicker yarn, and my invention can also be employed for the purpose of increasing the gage of a portion of the stitches in a course

40 or courses beyond the extent necessary to accommodate a reinforcing yarn or a thicker yarn for the express purpose of making a portion of the resulting fabric containing such stitches of increased gage actually 45 longer and wider than the portion of the fabric formed by the other portions of corresponding courses, the stitches of which are not increased in gage, as for example, in the sole portion of a stocking, and in the

50 heel and toe portions thereof, for the purpose of fashioning the stocking to the foot and providing additional room for the sole, heel, and toe, thereof, in accordance with the invention of Edward E. Kilbourn, William E. Smith and Isaac W. Kilbourn covered by

our former application for Letters Patent of the United States, filed Sept. 23, 1909, and given Serial No. 509,202. My invention also finds an additional use in that it may be employed for the purpose of increasing the gage of stitches at any part of the course or courses or at several different points in a course for any such purpose for which a stitch or stitches of increased gage may be or become desirable.

65

In the accompanying drawings I have selected for the purpose of illustrating my invention, several forms of devices and have shown the same in connection with a simple form of circular knitting machine in which a knitting cylinder carrying the needles is given a rotary motion with respect to stationary knitting cams, and in which the sinkers are given a horizontal reciprocatory motion toward and from the center of the knitting cylinder, such being a common form of knitting machine to which my invention is applicable, but it will be understood that my invention is also applicable to any form of knitting machine in which a relative circular movement between the knitting cylinder and the cam or cams is provided and in which the sinkers are not given a horizontal reciprocating movement or in other words, my invention is applicable to any knitting machine whatsoever in which the sinkers between the several needles of the circular series may be given an independent vertical movement.

70

80

85

In the accompanying drawings, Figure 1 represents more or less diagrammatically so much of a knitting machine as is necessary for a clear understanding of my invention, portions of the figure being shown in section. Fig. 2 is a diagrammatic top plan view of the parts shown in Fig. 1. Fig. 3 is a partial top plan view illustrating a modification of the invention. Fig. 4 is a top plan view similar to Fig. 2 illustrating another modification of my invention. Fig. 5 is a view similar to Fig. 1 illustrating the modification shown in Fig. 4. Fig. 6 is a detail of the actuating cam and a portion of the series of sinkers. Figs. 7 and 8 illustrate one form of sinkers which may advantageously be employed in connection with my invention showing one short sinker in Fig. 7 and one long sinker in Fig. 8.

90

95

100

105

In carrying out my invention, I provide means for increasing the gage of certain

110

stitches in a course or courses by raising to a greater or less extent the sinkers located adjacent to the needles on which the stitches of increased gage are to be formed, thereby causing the needles to draw stitches of increased gage between the sinkers so elevated for this particular purpose.

In the form of my invention shown in Figs. 1 and 2, 1 represents the needle cylinder, 2 represents one of the needles of the circular series adapted to reciprocate vertically therein and provided with a nib 3 for engaging the knitting cam 26. Relative circular movement is provided between the needle cylinder and the knitting cam in any desired or usual manner to effect the vertical movements of the needles for the production of a circular course of stitches either by rotating or reciprocating the cylinder with respect to the cam or cams or by rotating or reciprocating the cam or cams with respect to the cylinder. 4 represents the sinkers which are located between adjacent needles and are provided with shoulders 5 for supporting the work, the length or gage of the stitches being determined by the distance below the shoulder 5, to which the hook of the needle is drawn down by the knitting cam. The sinkers in this instance are shown as provided with horizontally disposed guiding portions 6 extending inwardly and also outwardly with respect to the axis of the knitting cylinder, from the main or vertically disposed portion of the sinker, the outwardly extending portion being provided with a nib 7 which is engaged by a horizontal ring 8 provided with a cam groove therein to engage the nibs 7 and impart the desired horizontal reciprocatory movement to the sinkers, as is usual in knitting machines, although the nibs 7 and cam ring 8 may be omitted if desired. It will be understood that where the cam ring 8 is employed there will be a relative movement between the cylinder and ring corresponding to the relative movement between the cylinder and the knitting cam which may be accomplished by rotating or reciprocating the cylinder with respect to the said ring 8 or by rotating or reciprocating the ring with respect to the cylinder. The sinkers adjacent to the needles which are to draw the stitches of greater or increased gage have their horizontal portions provided in this instance with extensions 9 projecting inwardly toward the center as shown in Figs. 1 and 8, of the drawings, while the sinkers adjacent to the needles which are to draw the normal stitch at all times are not provided with such extensions, as shown in Fig. 7, and as indicated by the dotted line 10 in Fig. 1. Each of the sinkers provided with the extension 9 is so arranged as to be capable of slight vertical movement with respect to the needle cylinder 1 and for convenience in assem-

bling the parts I prefer to provide the said sinkers with a notch 11 for engaging the sinker retaining ring 12 of increased vertical width over the width of the corresponding notch of the ordinary sinkers, to permit the vertical movement of the sinkers having the inward extending projections 9. For convenience of manufacture, however, all of the sinkers may be constructed alike in respect of the retaining recess 11, if desired, as the sinkers which are not raised, as hereinafter described, will be held in their lowest position by the downward pull of the needle and of the work. As shown in Fig. 1, I provide a vertically movable adjusting ring or sleeve 15 within the cylinder 1 which is preferably secured thereto in any desired manner as by screw 16 engaging a vertically disposed slot 17 in the sleeve 15 so that the sleeve 15 and knitting cylinder 1 will be held against relative circular movement while the sleeve is permitted a vertical movement with respect to the cylinder 1. Vertical movement may be imparted to the sleeve 15 in any desired manner as by means of the eccentric 18 on a rock shaft 19 mounted in a suitable bearing 20 and provided with an adjusting lever 21 for example, as shown in Figs. 1 and 2, the adjustment being made either by hand in which case the rock shaft 19 may be locked in its adjusted position by means of a set screw 22, or preferably the rock shaft will be operated by the pattern mechanism of the machine, which may be operatively connected with the lever 21 in any well known or usual manner to effect the vertical movement of the sleeve 15 at the desired time in the operation of knitting the stocking, in which case the set screw 22 may be omitted. The upper end of the sleeve 15 is preferably provided with a cylindrical portion 23 of less diameter than the cylinder, the upper end of which engages the inwardly projecting extensions 9 of those sinkers adjacent to the needles, the stitches of which are to be increased in gage. When therefore the sleeve 15 is moved upward a greater or less extent the sinkers whose projections 9 overlie the portion 23 of said sleeve will be correspondingly elevated and the stitches drawn by the adjacent needles will be increased in gage a greater or less extent corresponding to the amount of movement imparted to the sleeve 15. In this construction, supposing it to be desired that the stitches of the rear half of the stocking corresponding to the high-spliced portion, the heel portion, the sole portion, and the toe portion thereof, are to be increased in gage during the knitting of the corresponding portion of the stocking, it is only necessary to provide those needles which knit the rear half of the stocking with sinkers having inwardly projecting extensions 9 and to operate the adjusting sleeve 15

at the desired time and to the desired extent to secure the results desired. For example, the sleeve 15 can be elevated slightly while the high spliced portion above the heel is being knit to facilitate the insertion of a reinforcing thread in that portion of the stocking without increasing the length of the resulting fabric beyond that of the corresponding courses on the front of the leg.

10 When the heel is knit the sleeve 15 can be raised to a greater extent to facilitate the insertion of a heavier reinforcing thread, or the use of a still thicker knitting thread for the production of a heavy heel. When the

15 sole is knit, the sleeve 15 can be elevated sufficiently to positively increase the length of the fabric beyond the length of the corresponding fabric of the top of the foot, and at the same time to permit a reinforcing thread to be inserted or a heavier knitting thread to be used, and in knitting the toe the adjustment of the sleeve 15 may be made to facilitate the insertion of a reinforcing thread of the desired weight or the use of a heavier knitting thread. Obviously when the sleeve 15 is in its normal position, all the needles in the course will draw the same length stitches. If it is desired for special reasons to increase the gage of one or more stitches at several different points in a course, at any stage of the knitting of a stocking and at any position or positions in the course, it is only necessary to provide the sinkers adjacent to the needles forming such stitches with the inwardly projecting extensions 9 and this result may be accomplished to any desired extent according to the vertical adjustment of the sleeve 15.

40 In Fig. 3 I have shown a slight modification of my invention in which instead of providing the sleeve 15 with an annular portion 23 at the upper end thereof, I provide a semi-circular portion 23^a which is secured to the cylinder and adjustable vertically therein, and this portion 23^a may be carried upon a sleeve 15^a and vertically adjusted by the same means as shown in Figs. 1 and 2 or by other means, or the semi-circular portion 23^a may be carried by a half sleeve 50 suitably secured to the cylinder and vertically adjustable therein. Where the semi-circular elevating device 23^a is employed, it is immaterial how the sinkers which are not to be operated thereby are constructed and they may either have the short inner ends 10 as shown in Figs. 3 and 7, or all the sinkers may be made alike with the inwardly projecting extensions 9, as the extent of the semi-circular portion 23^a will determine and select which of the sinkers are to be raised when the elevating device is adjusted vertically.

55 In Figs. 4 and 5 and 6 I have shown another modification of my invention. In this form the apparatus instead of raising

simultaneously all of the sinkers, adjacent to the needles the stitches of which are to be increased in gage, I provide a cam for raising the particular sinkers adjacent to the needles whose stitches are to be increased, in gage, at the time when the said needles are drawn down by the knitting cam, to draw the stitch, it being obvious that such cam and the knitting cylinder will have the same relative circular movement with respect to each other as exists between the cylinder and the knitting cam, and in Figs. 4 and 5 I have shown a construction in which the sinker elevating cam is preferably held from rotary movement while the 70 cylinder and needles are rotated. In these figures 1^a represents the needle cylinder, 2^a a needle of the circular series provided with a cam engaging nib 3^a, and 4^a represents one of the sinkers which is to be elevated, and 75 which is provided with the inwardly projecting extension 9^a, which sinkers preferably extend halfway around the cylinder, as indicated diagrammatically in Fig. 4, the remaining half of the sinkers being without 80 such extensions 9^a as indicated at 10^a. 30 represents the sinker raising cam which in this instance is carried by a vertically disposed rod 31, mounted in a guide 32 and vertically movable therein, said rod being 85 provided with a collar 33 and carrying studs 34 engaged by yoke 35 on the adjusting lever 36, adapted to be operated by hand by means of a set screw 37, or the set screw 37 may be omitted and the arm 36 operated 100 directly by the pattern mechanism. The upper end of the cam 30 as shown in Fig. 6 will be so constructed as to engage the extensions 9^a of the sinkers so provided and elevate the sinkers to a greater or less extent, depending upon the adjustment of the cam 30, the cam being constructed to engage a plurality of said sinkers, at least two of 105 the same on opposite sides of the needle which is in the lowest position with respect to the knitting cylinder. Obviously the cam 30 is so located with respect to the knitting cam that it will operate upon the sinkers at the same time that the knitting cam has drawn down the appropriate needle 110 to its lowest position, thus increasing the gage of the stitch drawn by the needle and each successive needle of the series adjacent to the sinkers having the extensions 9^a. In this form of the invention, the selection of 115 the needles, the stitches of which are to be increased in gage, is effected by providing sinkers adjacent thereto and preferably on opposite sides thereof, with the sinkers having the extensions 9^a, and it will be obvious 120 that wherever the needles are so provided with sinkers having extensions 9^a to engage the cam 30, whether it be all of the needles knitting the back portion of the stocking, or certain of said needles at intervals in the 125 130

4
circular series, when the cam is raised high enough to engage and elevate the extensions 9^a, the stitches of those needles so provided will be increased in gage. It will also be 10 obvious that this form of the invention can be employed in machines wherein the cylinder is stationary by rotating the cam 30 with respect to the needle cylinder coincidentally with the knitting cam.

11 I do not desire to be limited to the exact details of the constructions shown in the several embodiments of my invention which I have selected for the purpose of illustrating the invention and shown and described 15 herein, as modifications may be made therein without departing from the spirit of my invention.

What I claim and desire to secure by Letters Patent is:—

- 20 1. In a circular stocking knitting machine, the combination with a needle cylinder, a circular series of vertical reciprocating needles, of stitch forming cam mechanism for actuating all of the needles to the same extent during tubular work, of a circular series of sinkers located between the needles, certain of said sinkers located between consecutive needles of a group of needles extending a portion of the way 25 around the circular series, being vertically movable, and means for vertically adjusting all of said consecutive vertically movable sinkers to increase the size of a plurality of consecutive stitches in each course of a segmental portion of the tubular fabric.
2. In a circular stocking knitting machine, the combination with a needle cylinder, a circular series of vertical reciprocating needles, and stitch forming cam mechanism for actuating all of the needles to the same extent during tubular work, of a circular series of sinkers located between the needles, all of the sinkers located between the successive needles for knitting the rear 40 half of the leg, the heel and toe pockets, and the sole of the foot of the stocking being vertically movable, and means for adjusting said consecutive vertically movable sinkers

vertically, whereby the sole portion of the stocking foot can be made materially longer 50 than the fabric formed by the corresponding courses of the top of the foot to fashion the stocking to fit the foot.

3. In a circular stocking knitting machine, the combination with a needle cylinder, a circular series of vertically reciprocating needles and cam mechanism for actuating all of the needles to the same extent when knitting tubular work, of a circular series of sinkers located between the needles, the sinkers adjacent to the successive needles which knit the sole of the stocking having inwardly projecting portions, and a vertically adjustable part within the knitting cylinder, for engaging and elevating said inwardly projecting portions of the sinkers adjacent to said sole knitting needles, whereby the sole is made longer and wider than the corresponding courses of the foot to fashion the stocking to fit the foot.

4. In a circular stocking knitting machine, the combination with a needle cylinder, a circular series of vertically reciprocating needles and cam mechanism for actuating all of the needles to the same extent 75 when knitting tubular work, of a circular series of sinkers located between the needles, the sinkers adjacent to the successive needles which knit the sole of the stocking having inwardly projecting portions, and a vertically adjustable part within the knitting cylinder, held in fixed relation, circularly, with respect to the knitting cam, for engaging said inwardly projecting portions of the successive sinkers adjacent to the sole knitting needles, whereby the sole of the stocking can be made longer and wider than corresponding courses of the top of the foot to fashion the stocking to fit the foot.

In testimony whereof I affix my signature, 90 in the presence of two witnesses.

WILLIAM E. SMITH.
